UNITED STATES PATENT OFFICE.

HERBERT E. PERCIVAL, OF GALVESTON, TEXAS, ASSIGNOR OF ONE-HALF TO BREWER W. KEY, OF WOODWARD, OKLAHOMA.

RAIL-FASTENING.

No. 874,535.

Specification of Letters Patent.

Patented Dec. 24, 1907.

Application filed January 29, 1906. Serial No. 298,308.

To all whom it may concern:

Be it known that I, HERBERT E. PERCIVAL, of Galveston, in the county of Galveston and State of Texas, a citizen of the United States, 5 have invented a new and useful Improvement in Rail-Fastenings, of which the following is a full, clear, and exact description, reference being had to the accompanying drawings, forming a part of this specification, 10 in explaining its nature.

My invention relates essentially to the cushioning of railroad ties in connection with, or as directed to improving the means for fastening the rails to the tie, and by 15 "railroad ties" I refer more especially to a railroad tie made of cement, for in connection with this kind of tie especially it has been found desirable, if not necessary, to insert between the rail and the tie a cushion 20 made of some elastic material, generally of wood, to take up the shock to which the tie is subjected.

The object of my invention is to adapt the cushion to the rail and to the means or spikes 25 for fastening the rail to the tie so that the spikes cannot spread away from, or leave the flanges of the rail with which they are properly in engagement, or become loosened.

My invention can best be seen and understood by reference to the drawings in which—

Figure 1 shows a sectional view of the improved fastening. Fig. 2 shows a plan of the same.

Referring to the drawings:—A represents 35 a portion of a cement tie, B a rail resting upon a cushion C, interposed between it and the tie, and D represents the spikes extending through the cushion and fastening the rail.

The cushion C is preferably made rectangular in shape and rests on the top of the tie 40 snugly in a recess *a* made to receive it. Instead of resting on the top surface of the cushion the rail rests or fit into a slot *c* cut therein. This slot is cut just so deep that the 45 tops of the flanges *b* of the rail are on a line with the top surface of the cushion so that the head *d* of the spikes D, which pass through the cushion at points adjacent to the flanges of the rail, will engage partly with said flanges 50 and partly with the adjacent surface of the cushion. The resulting advantage is that the cushion supporting the heads of the spikes on the outside, keeps them from

spreading or leaving the flanges of the rail when subjected to heavy traffic. Then 55 again, by thus giving an outer support to the heads of the spikes keeps the spikes from becoming loosened. With reference to the spikes D, I prefer that they be a threaded or screw spike especially if used in connection 60 with a cement tie. A driven spike may, however, successfully be used, as above described.

While I have already stated that my invention is especially adapted to be used in 65 connection with a cement tie, it can also be advantageously practiced with a common wood tie, the cushion in addition to the advantages above set forth having, also, the additional advantage of preventing the rail 70 from cutting into the surface of the tie.

Having thus fully described my invention, I claim and desire to secure by Letters Patent of the United States:—

1. In combination with a railroad tie, a 75 cushion resting thereon, a rail resting on said cushion and fitting into a slot cut therein, which slot is cut so deep that the upper surface of the flange of the rail will be on a line with the surface of said cushion, and means 80 for fastening said rail to said tie, which means is adapted to engage partly with the flange of said rail and partly with the surface of said cushion and be supported thereby, substantially as described. 85

2. In combination with a cement railroad tie having a recess cut in the top thereof, a cushion fitting within said recess, a rail resting on said cushion and fitting into a slot cut therein, which slot is cut so deep that the 90 upper surface of the flange of the rail will be on a line with the upper surface of said cushion, and means alongside the flange of said rail fastening down through said cushion into said tie, which means is adapted to 95 engage partly with the flange of said rail on the inside and the surface of said cushion on the outside, whereby said means may be supported by said cushion so as to be held in proper engagement with the flange of said 100 rail.

HERBERT E. PERCIVAL.

In presence of:

A. S. HEATON,
E. SHOPHOFEN.
